FUSE PLUG

John Corser, Minneapolis, Minn.

Application March 5, 1936, Serial No. 67,392
Renewed July 30, 1937

20 Claims. (Cl. 200—130)

This invention relates to fuse plugs of that type adapted to be screwed into sockets. Such plugs usually have been provided with fuses located back of mica disks. They have been objectionable because the mica has added to the cost; because it is difficult to see the fuses through the mica; and because the plugs can be reinserted, when burned out, with coins or other metallic objects inserted to bridge the fuse.

10 An object of the present invention is to eliminate the mica and to provide a means whereby, when the fuse is burned out, it will not fit the socket, thus positively indicating to the user that the fuse is useless and a new plug must be used.

15 With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

20 In the accompanying drawing the preferred forms of the invention have been shown.

In said drawing:

Figure 1 is a central section taken longitudinally through the plug.

25 Figure 2 is a side elevation.

Figure 3 is a section on line 3—3, Figure 1.

Figure 4 is a view similar to Figure 1 showing a modified construction.

Figure 5 is a side elevation thereof.

Figure 6 is a section through another form.

30 Referring to the figures by characters of reference, 1 designates a plug of porcelain or other suitable insulating material having a radial slot 2 extending thereinto from one end and intersected at its outer side by a groove 3 extending partly around the plug.

35 A sleeve 4 of conductive material is fitted on the plug and is screw-threaded so as to engage properly in the usual socket. This sleeve is slotted at 5 to form a tongue 6 extending longitudinally of groove 3 and interrupting the thread on the sleeve. As the sleeve is of resilient material the tongue is likewise resilient.

40 A contact 7 is located at the center of one end of the plug 1 and is formed on one end of an anchoring strip 8 which is also a conductor. This strip is fitted in the plug 1 at the inner end of slot 2 and is joined to the tongue 6 by the fuse 9. Thus the tongue is held normally retracted back 45 in groove 3 as shown.

The plug is adapted to be inserted into a fuse receptacle or socket in the usual way. When the fuse is burned out it releases the tongue 6. Therefore, when the plug is removed for inspection the released tongue will spring out of the groove 3 as shown by broken lines in Figure 3 and indicate to the user that the fuse is useless. It will also act as a baffle to prevent the plug from being reinserted into the receptacle for the purpose of holding a coin or the like in position.

10 In Figures 4 and 5 the plug 10 has been shown with its threaded sleeve 11 slotted at 12 to provide a tongue 13 extending along a longitudinal groove 14 in the plug. This tongue is also held normally under restraint by a fuse 15 joined to a conductor 16 in the plug and leading from contact 17.

15 In this modified structure the operation is the same as that heretofore described. When the fuse is burned it releases the tongue 13 which is thus free to spring outwardly as shown by broken lines in Figure 4, thus to form a baffle.

20 In Figure 6 the plug 18 has a diametrical opening 19 and a radial recess 20 both opening into a longitudinal groove 21. The threaded sleeve 22 on the plug has an opening 23 aligned with recess 20 and is also formed with an inwardly extended ear 24 overhanging the opening. This ear supports a tongue 25 which laps a flange 26 on a plunger 27. The plunger is seated in recess 20 and a spring 28 is also located in said recess.

25 A contact 29 is located at one end of the plug and is held in place by a combined conductor and anchoring strip 30 seated in the plug. A fuse 31 connects this strip to the tongue 25 and the tongue, in turn, holds the plunger normally pressed back into recess 20 so as to maintain the spring under compression.

30 When the fuse is burned it releases tongue 25 and the plunger 27 thus is free to be projected by its spring so as to extend outwardly beyond the threaded sleeve 22 to form a baffle as soon as the plug is removed from its receptacle or socket. Thus reinsertion of the plug into the receptacle 35 is prevented.

35 What is claimed is:

1. A plug, a fuse, and means released by the fuse when burned for preventing insertion of the plug into a receptacle.

40 2. A fuse plug for insertion into a fuse receptacle before the fuse is burned and removable from the receptacle before or after the fuse is burned, said fuse plug comprising a plug, a baffle movable laterally to position beyond the 45

plug, and a fuse for holding the baffle normally retracted into the plug.

3. A plug, a sleeve thereon, a contact, a baffle movably mounted relative to the sleeve, and a fuse connection between the contact and baffle 5 for holding the baffle normally retracted into the sleeve and plug.

4. A plug, a sleeve thereon, a baffle carried by the sleeve and mounted to spring outwardly relative thereto when unrestrained, and a fuse for 10 holding the baffle against movement.

5. A plug, a sleeve thereon, a resilient baffle carried by the sleeve and mounted to spring outwardly relative thereto when unrestrained, and a fuse for holding the baffle under restraint.

15. 6. A plug, a threaded sleeve thereon, a resilient baffle carried by the sleeve and extending partly therearound, said baffle being mounted to spring outwardly relative to the sleeve when unrestrained, and a fuse in the plug for holding the 20 baffle under restraint.

7. A plug, a threaded sleeve thereon, a resilient baffle carried by the sleeve and interrupting the thread, said baffle being mounted to spring outwardly relative to the sleeve when unrestrained, 25 and a fuse in the plug for holding the baffle under restraint.

8. A plug, an apertured sleeve thereon, a spring actuated plunger in the plug, and fuse restrained means for holding the plunger normally retracted in the plug, said plunger when 30 released being movable into the aperture and outwardly from the sleeve.

9. A plug, a fuse therein, and means controlled by the fuse for preventing insertion of the plug into a receptacle when said fuse has 35 burned.

10. A plug, a fuse therein, and spring means released by the fuse when burned for thereafter preventing insertion of the plug into a receptacle.

40 11. A plug, a fuse therein and spring controlled means released by the fuse when burned for preventing insertion of the plug into a receptacle.

12. A plug fuse adapted for insertion in a 45 fuse receptacle and including a fuse and non-current carrying means normally retracted into the plug and adapted to be released by the fuse when burned for preventing insertion of the plug into a receptacle.

50

13. A plug fuse adapted to be inserted in a fuse receptacle and including a plug body, a fuse therein and normally non-current-carrying means controlled by the fuse for preventing insertion of the fuse into a receptacle after burning of the fuse. 5

14. A plug fuse adapted to be inserted in a fuse receptacle and including a plug body, a fuse therein and non-current carrying means controlled by the fuse for preventing insertion of the 10 fuse into a receptacle after burning of the fuse.

15. A plug fuse adapted for insertion into a fuse receptacle and including a plug body, a fuse and means biased to extend beyond the periphery of the plug body adapted to prevent insertion 15 of the plug into a plug receptacle and normally held by the fuse within the periphery of the plug body.

16. A plug fuse adapted for insertion into a fuse receptacle and including a fuse and means 20 controlled by movement of at least a part of said fuse when burned for thereafter preventing insertion of the plug into a receptacle.

17. A plug fuse adapted for insertion into a receptacle and comprising a plug body, a fuse supported thereby and fuse-controlled normally ineffective means adapted to prevent insertion of a plug fuse into a receptacle, said means being rendered effective on burning of the fuse. 25

18. A circuit protector comprising a plug body, 30 a circuit opening means therein having a portion thereof adapted to be moved during circuit-opening operation thereof and a baffle biased to have a portion thereof project beyond the external periphery of the plug body to prevent insertion of the protector into a receptacle and normally restrained within the periphery of the 35 plug body by the circuit opening means.

19. A plug fuse adapted for insertion into a receptacle and comprising a plug body, a fuse 40 therein and normally-ineffective means for preventing insertion of a plug fuse into a receptacle said means becoming effective on removal of a burned out plug fuse from a receptacle.

20. A plug fuse as set forth in claim 10 in which 45 said spring means comprises a part of the current-traversed elements of the plug fuse.

JOHN CORSER.
